OTHER PUBLICATIONS

Photograph of a fingernail polish bottle in the design of a Teddy bear, manufactured by Interco of Germany, believed to have been offered for sale in the United States in Jun. 1997.

Primary Examiner—Dominic Simone
Attorney, Agent, or Firm—Dennis H. Lambert, Esq.

[57]

CLAIM

We claim the ornamental design for a fingernail polish bottle, as shown and described.

DESCRIPTION

FIG. 1 is a right front perspective view of a fingernail polish bottle showing our new design;
 FIG. 2 is a front elevational view thereof;
 FIG. 3 is a right side elevational view thereof, the left side being a mirror image; and,
 FIG. 4 is a left, rear bottom perspective view thereof.
